UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

CAR CONSTRUCTION

Application filed August 9, 1929. Serial No. 384,777.

This invention relates to improvements in car construction.

One object of the invention is to provide a car construction including draft sills adapted to receive buffing and draft shocks, wherein the car body is longitudinally movable with respect to the draft sills to a limited extent and is cushioned with respect thereto, and the draft sills are also yieldable in a lengthwise direction to cushion shocks to which the car is subjected in service.

Another object of the invention is to provide a car construction including longitudinally disposed draft sills with respect to which the car body is longitudinally movable to a limited extent, wherein cushioning means reacts between the draft sills and the car body to yieldingly oppose relative movement thereof to take care of buffing and draft shocks and the draft sills are themselves yieldingly extensible lengthwise of the car to cushion draft shocks.

A further object of the invention is to provide a car construction wherein the body of the car and the draft sills have limited relative movement lengthwise with respect to each other, yieldingly opposed by shock absorbing means to take care of buffing and draft shocks, and in addition the sills themselves are yieldingly compressible lengthwise of the car to take care of buffing shocks.

Still another object of the invention is to provide a railway car construction including draft sill members disposed lengthwise of the car, each draft sill member having coupler means connected to the outer end thereof and the sill members being yieldingly connected at their inner ends to permit a limited amount of relative movement therebetween, and the car body and the connected draft sill members have limited relative movement with respect to each other which is yieldingly resisted.

A further object of the invention is to provide a car construction including a continuous draft sill structure extending from one end of the car to the other and with respect to which the car body is movable lengthwise to a limited extent, wherein the draft sill structure comprises separate sill members con-

nected at their inner ends to form the continuous draft sill structure, wherein the connection is yieldable to permit relative longitudinal movement of said sill members with respect to each other to a limited extent and wherein shock absorbing means is interposed between the continuous draft sill structure and the car body to yieldingly resist relative longitudinal movement of the same in both buff and draft.

A more specific object of the invention is to provide a railway car construction including coupler means at opposite ends of the car, draft sill members connected to each coupler and extending inwardly of the car, the draft sill members connected to one of the couplers being connected to the draft sill members of the other coupler by a shock absorbing mechanism permitting yielding limited relative movement of the sills with respect to each other lengthwise of the car, the shock absorbing means comprising a plurality of transversely disposed, laminated plate spring members mounted in a floating carrier and engaging abutment means on the respective sills, the sill members together with the shock absorbing means forming a continuous draft sill structure from end to end of the car which is relatively movable with respect to the car body and to which the same is connected by shock absorbing means permitting a predetermined amount of yieldingly resisted relative movement therebetween in a lengthwise direction.

Other objects of the invention will more clearly appear from the description and claims hereinafter following.

In the drawings, forming a part of this specification, Figures 1, 2 and 3 are horizontal, longitudinal sectional views through the underframe structure of a railway car illustrating my improvements in connection therewith, Figure 1 showing the structure at one end of the car, Figure 2 showing the structure at the central portion of the car, said figure being a continuation of Figure 1, and Figure 3 showing the other end of the car structure and being a continuation of Figure 2. Figure 4 is a top plan view of the structure at the center of the car, the parts

being shown on an enlarged scale. Figure 5 is a vertical, longitudinal sectional view corresponding substantially to the line 5—5 of Figure 4. And Figure 6 is a transverse, vertical sectional view corresponding substantially to the line 6—6 of Figure 5.

Referring to the drawings, 10—10 indicate the body bolsters at the opposite ends of the car in connection with which my improved movable draft sill structure is slidably supported. Coupler means of well known form indicated by 11—11 is employed at each end of the car, the couplers being only partly shown, the head portions thereof being broken away.

My improved car construction comprises broadly two pairs of longitudinally disposed spaced sill members 12—12, a floating carrier 13, two sets of laminated plate springs 14—14, coupler keys 15—15 for connecting the couplers to the sills; shock absorbing means 16—16 cooperating with the couplers and spring shock absorbing means 17—17 opposing relative movement of the sills and the bolsters.

The sill members are arranged in pairs at opposite ends of the car, the same being preferably of the usual channel shape section and spaced the standard distance apart. Each 30 pair of sills 12 extends inwardly from the corresponding end of the car to a point approximately at the center of the car, the sills of the two pairs being disposed in alinement and having their inner ends spaced apart a 35 predetermined distance, preferably about three inches. The sill members are slidably supported in any suitable manner in connection with the body bolsters 10 of the car.

The coupler 11 at each end of the car is 40 connected to the outer ends of the corresponding sills by the coupler key 15 of the usual type, the sills being slotted to accommodate the opposite ends of the key and the key extending through the usual opening of the 45 coupler shank. The outer end portions of each pair of sills are reinforced and braced by a spacing casting 18 which may be secured to the webs of the sills in any suitable manner, the same being herein shown as riveted. The casting 18 is provided with spaced 50 forwardly extending side arms 19—19 which have coupler key-receiving openings 20—20 in substantial alinement with the openings of the sills. As shown, the key-receiving openings 55 of the casting and the sills are of such a length as to permit a certain amount of relative movement between the coupler and the corresponding pair of sills. At the rear end, the casting 18 is provided with a pocket 60 21 in which is disposed a shock absorbing spring 22, the spring cooperating with the corresponding coupler 11, a follower 23 being interposed between the inner end of the coupler shank and the spring. As shown 65 each casting 18 is provided with front limit

ing stop shoulders 24—24 which cooperate with the follower 23 to limit outward movement thereof with respect to the corresponding pair of sills 12. As most clearly shown in Figures 1 and 3, spring follower discs or caps are associated with the opposite ends of each spring 22, the caps being connected by a retainer bolt which limits the expansion of the spring. As will be evident, the expansive action of the spring 22 holds the follower and the associated coupler in outermost position with the coupler key in engagement with the front end walls of the slots of the sills of the casting 18. As will be evident, when a draft or pulling action is applied to the coupler, the corresponding pair of sills 12 will be pulled outwardly therewith. Upon a buffing action being applied to this coupler, the sills will be forced yieldingly inwardly due to the compression of the spring 22 until the coupler key engages the inner end walls of the key slots of the sills and the casting 18, whereupon the pair of sills will be forced to move inwardly in unison with the coupler.

The two pairs of sills associated with the couplers 11 at opposite ends of the car are connected at their inner ends to provide a substantially continuous sill structure extending from one end of the car to the other, which sill structure is movable with respect to the 95 car body in a lengthwise direction. The connecting means for the two pairs of sills comprises the floating carrier 13 and the laminated plate springs 14—14. The carrier 13 is in the form of a casting having front and rear transversely extending openings or pockets 25—25 in which the two sets of laminated plate springs 14—14 are disposed. As most clearly illustrated in Figures 2 and 4, the 100 opposed front and rear walls of each opening or pocket are curved transversely and are preferably convex. The casting 13 has top and bottom plates 26—26 detachably secured thereto, the plates overlapping the top and bottom flanges of the two pairs of draft sills 12 as clearly shown in Figures 4 and 6. As will be evident, the floating carrier or 105 casting 13 is thus guided by the sills for longitudinal movement with respect thereto and holds the inner ends of the two pairs of sills in alinement. The plates 26 are spaced respectively from the top and bottom sides of the carrier as clearly shown in Figures 5 and 6, the carrier walls being provided with a plurality of bosses 27—27 which the plates 26 abut. The plates may be secured to the carrier 13 in any suitable manner and are herein shown as secured thereto by a plurality of bolts 28—28 which extend entirely through the carrier and alined openings in the bosses 27. The casting or carrier 13 is of such a 110 width that the opposite side faces thereof are spaced an appreciable distance from the inner sides of the webs of the pairs of sills 12—12. This spacing is provided in order 115 120 125 130

- to accommodate stop members 29—29 which are secured to the respective pairs of sills. As mostly clearly illustrated in Figures 2, 4 and 5, each pair of sills 12 is provided with 5 two such stop members at the inner end thereof. Each stop member is in the form of a relatively heavy casting, suitably reinforced by ribs, and having spaced abutment shoulders or lugs 30—30 on the inner side thereof. 10 As shown, the inner faces of the lugs 30—30 of each casting preferably diverge laterally inwardly and are spaced apart such a distance as to embrace the corresponding outer end of the set of laminated plate spring members 15 at the corresponding end of the carrier 13. The laminated plate spring members 14 are each composed of a plurality of rectangular plate springs which are preferably substantially straight and of such a length that 20 the opposite ends of each set will engage with in the pockets provided between the stop lugs 30—30 on the corresponding pairs of sills 12—12. The lugs 30 are of such a depth that there is no danger of the ends of the 25 springs becoming disengaged therefrom when the plate springs are flexed to their limit, that is when flexing thereof is limited by full contact with one of the curved bearing surfaces of the corresponding pocket of 30 the carrier 13. The parts are so proportioned that the inner ends of the two pairs of sills are held normally spaced apart by the connecting laminated plate springs and carrier, the distance shown in the drawings. 35 Each casting 29 is provided with a forwardly extending bracing portion 31 to reinforce the sill structure. A spacing thimble 32 is preferably interposed between the sections 31—31 of the two opposed castings of 40 each pair of sills and the sills are connected by a bolt 33 extending through the thimble, the sections 31 of the castings 29 and the webs of the sills. As will be evident, the inner ends of each pair of sills are thus maintained 45 a fixed distance apart and thoroughly braced. The spring shock absorbing means 17 at each end of the car, which opposes relative movement of the corresponding pair of sills of the bolster 10 at that end of the car preferably comprises elongated coil spring members co-operating with front and rear follower plates 33—33 which in turn cooperate with inner and outer stop lugs 34—34 fixed to the inner sides of the sills 12. The inner 50 follower 33 is anchored to the corresponding bolster 10 by elongated rods or bars 35—35 which extend through the coils of the two springs and openings provided in the two followers 33. The inner ends of the bars 35 are provided with retaining cotter pins 36—36 or any other suitable means for engagement with the inner follower 33 to limit the inward movement of the same. In the 55 present instance, the bars 35 are shown as anchored to the bolster casting by pins 37—37 extending through the outer ends of these bars. In order to further brace the pairs of draft sills, and hold the same spaced the proper distance apart, additional spacing plates 38 and 39 may be employed between the bolsters and the inner ends of the sills. 70 The operation of the draft rigging of my improved car construction is as follows: When a pulling action is applied to either of the couplers 11, the same will be pulled outwardly, thereby also pulling the corresponding pair of draft sills 12 outwardly by means of the connecting coupler key 15. During the outward movement of the pair of sills, the springs 17 associated therewith will be compressed between the followers 33—33, the outer follower 33 being held stationary by engagement with the filler casting of the corresponding bolster and the inner follower 33 being pulled forwardly by the lugs 34 cooperating therewith. During the described action, a pull will also be exerted on the laminated plate spring members 14 cooperating with the pair of sills referred to. Inasmuch as the other set of laminated plate 80 springs engages the lugs on the other pair of sills, and the two sets of laminated plate springs are mounted in the carrier 13, there will be a tendency for the last named pair of sills to move together with the sills at the other end of the car. Inasmuch as movement of both pairs of sills is resisted by the springs 17, the pair of sills at the right hand end of the car as viewed in Figures 1, 2 and 3 will be retarded in their movement and the 85 springs 14—14 will be flexed. In resisting the movement of the right hand pair of sills, the corresponding springs 17 are compressed between the followers 33 at the same end of the car, the outer follower 33 being pulled by the cooperating lugs 34 and the inner follower 33 being held stationary by the rods or bars 35 to which this follower is anchored. As will be evident, there is thus a yield of the 90 continuous draft sill structure comprising 100 the two pairs of sills and a connecting means including the carrier 33 and the laminated plate springs 14, the entire continuous draft sill structure being thus elongated. The separation of the two pairs of sills lengthwise of the car will be limited when the laminated plate springs 14 are flexed to such an extent that they contact with the convex bearing surfaces of the carrier 33 throughout the 105 width of the same. When the actuating force is reduced, the tendency of the laminated plate springs to assume their normal straight position will restore the sills to the relative 110 position shown in Figures 1, 2 and 3 and the action of the springs 17 will restore the two pairs of sills to the centered position with respect to the car body. Upon an inward or 115 buffering movement being applied to either of the couplers 11, and referring particularly to the coupler 11 at the lefthand end of the 120 125 130

car as shown in Figure 1, the spring 16 will be first compressed, inasmuch as the same is much lighter than the other springs of the shock absorbing means associated with the sills 12. As the coupler is forced inwardly, the key 15 thereof will engage the inner end walls of the key slots of the casting 18 and of the corresponding pair of draft sills 12, thereby causing these sills to move inwardly in unison with the coupler. During this action, the outer follower 33 will be forced inwardly by the lugs 34 cooperating therewith, compressing the springs 17 which bear at their inner ends on the inner follower 33, which is held stationary with respect to the car body by the bars 35. During the described movement of the sills 12, the pair of sills 12 at the righthand end of the car will be forced in the same direction also, due to the connecting means between the sills comprising the two sets of laminated plate springs 14 and the carrier 13. As hereinbefore pointed out, the plates 14 will be flexed during the time that motion is transmitted from one pair of sills to the other. Movement of the sills 12 at the right hand end of the car will be resisted by the corresponding springs 17. Relative approach of the two pairs of sills lengthwise of the car, during the described action, will be limited by engagement of the inner ends of two pairs of sills with each other. The parts are preferably so proportioned that when the sills thus engage each other flexing of the springs 14 will also be limited by full engagement with the convex bearing surfaces of the carrier 13.

It will be appreciated that during operation of the car in service, the entire car body is capable of lengthwise movement with respect to the continuous draft sill structure substantially independently of relative longitudinal movement of the two pairs of sills with respect to each other, this movement of the car body with respect to the combined sill structure being yieldingly resisted by the springs 17. It is further pointed out that the shock absorbing means comprising the springs 14 which connect the two pairs of sills may be fully actuated to the limit of its movement before the springs 17 have been compressed to any great extent, whereupon the connected pairs of sills 12 will move in substantial unison, thus forming in effect a continuous draft sill structure from end to end of the car, which is substantially rigid.

The yielding connection between the sills, in addition to affording simple and efficient shock absorbing means, also prevents distortion of the sills due to heavy shocks being applied thereto inasmuch as the continuous draft sill structure is compressible lengthwise to the extent of flexing movement of the springs 14. The yielding draft sill construction further facilitates starting of the train

of cars in that it permits the movement of the pair of sills at one end of the car with respect to the pair at the opposite end of the car whereby the cars of the train are set in motion successively.

I have herein shown and described what I now consider the preferred manner of carrying out my invention, but the same is merely illustrative and I contemplate all changes and modifications that come within the scope of the claims appended hereto.

I claim:

1. In car construction, the combination with body bolsters at opposite ends of the car; of coupler means at each end of the car; a pair of spaced draft sills connected to each coupler and extending inwardly of the car, said sills being movable with respect to the bolsters; means for yieldingly connecting said sills of each pair to one of said bolsters; and means connecting the pair of sills associated with one coupler means to the pair of sills associated with the other coupler means, including a floating carrier embraced between the inner ends of said pairs of sills, said carrier having transverse abutment faces, transversely disposed laminated plate springs interposed between each set of abutment faces, and means connecting one of said last named springs to one pair of sills and connecting the other laminated plate spring to the other pair of sills, comprising stop shoulders on each pair of sills embracing the opposite ends of the corresponding plate spring.

2. In car construction, the combination with a pair of movable draft sills at each end of the car, the members of each pair of sills being spaced apart laterally and having pairs of spaced stop shoulders at their inner ends, the sills of said pairs extending inwardly from the opposite ends of the car, said pairs having their inner ends normally spaced apart, and said inner ends being engageable with each other to limit the approach of the sills in buff; shock absorbing means opposing movement of each pair of sills with respect to the car in both buff and draft; and yielding connecting means for said pairs of sills, yieldingly opposing relative movement of one pair with respect to the other in both buff and draft, said connecting means including a casting having a pair of spring pockets at opposite ends and spring means within each pocket having shouldered engagement with the pairs of stop shoulders of the corresponding pair of sills, the compression of said connecting means being limited in buff by the engagement of the inner ends of said pairs of sills with each other.

In witness that I claim the foregoing I have hereunto subscribed my name this 7th day of August, 1929.

JOHN F. O'CONNOR.
